UNITED STATES PATENT OFFICE.

OLIVER P. FRITCHLE, OF CHICAGO, ILLINOIS.

DESIGN FOR A RADIOCABINET.

Application filed May 7, 1928. Serial No. 26,600. Term of patent 14 years.

To all whom it may concern:

Be it known that I, OLIVER P. FRITCHLE, a citizen of the United States, residing at Chicago, in the county of Cook and State of Illinois, have invented a new, original, and ornamental Design for Radiocabinets, of which the following is a specification, reference being had to the accompanying drawing, forming part thereof.

The figure is a perspective view of a radio cabinet, showing my new design.

I claim:

The ornamental design for a radiocabinet, as shown.

OLIVER P. FRITCHLE.
